UNITED STATES PATENT OFFICE

2,522,020

AUTOMATIC CHRISTMAS TREE FIRE
EXTINGUISHER

Leonard C. Deyo, Lewiston, Idaho

Application December 3, 1947, Serial No. 789,535

1 Claim. (Cl. 169—26)

2

This invention relates to an automatic Christmas tree fire extinguisher.

It is an object of the present invention to provide a fire extinguisher particularly adapted to be fitted on a Christmas tree and wherein the part containing the extinguishing fluid is of ornamental design but fragile to be opened for spreading the fluid over the tree, the opening of the container being effected automatically when a predetermined temperature, resulting from a flame, has been effected.

Other objects of the present invention are to provide an automatic Christmas tree fire extinguisher which is of simple construction, inexpensive to manufacture and efficient in operation.

For other objects and for a better understanding of the invention, reference may be had to the following detailed description taken in connection with the accompanying drawing, in which

Fig. 1 is a front elevational view of the fire extinguisher connected to the tree to locate the fluid container at the top thereof.

Fig. 2 is a fragmentary and sectional view of the extinguisher taken on line 2—2 of Fig. 1.

Fig. 3 is a transverse sectional view taken through the clamp of the support for attaching the support to the tree and as viewed on line 3—3 of Fig. 1.

Fig. 4 is a fragmentary side elevational view of the extinguisher after the frangible container has been broken to discharge the fluid.

Fig. 5 is a fragmentary transverse sectional view taken through the support and the inner wall of the container and showing the connection of the container with the support, the view being taken on line 5—5 of Fig. 4.

Fig. 6 is a fragmentary front elevational view of the extinguisher showing a different shaped container for the fluid.

Referring now to the figures, 10 represents a support having spring clamps 11 thereon serving to attach the support to the tree. This support 10 is in the form of a rod which is threaded at its upper end as indicated at 12. A knurled supporting nut 13 is adjustable upon the threaded end 12. This nut will support a loop projection 14 extending from a frangible container 15. As the nut 13 is adjusted, the container will be elevated to a different height or level removed from a plate or disc 16 which serves to break the fluid container as shown in Fig. 4. This plate 16 is normally retained in a position to compress a spring 17 by solder material 18. The spring 17 is anchored to the rod by a rivet 19. As the plate 16 is released, it will

break the container 15. The soldering material is connected between the rod 10 and the plate 16 in only such amount as to be easily separable therefrom when heat is conducted to the same as by way of the conduction of the heat along the rod 10 which is of metal.

The fluid will drop onto the plate 16 and will be spread outwardly in all directions so as to be extended to all sides of the tree. Accordingly 10 the plate 16 serves as a deflector for the fluid.

Also extending from the rear of the container 15 is a loop projection 21 adapted to surround the upper end of the rod whereby to support the upper portions of the container and to maintain the same upright on the rod. A lock nut 22 will prevent the container from being removed from the rod. As the container is elevated on the rod the nut 22 must be released.

In Fig. 6 there is shown a modified form of 20 container as indicated at 23. This shows that the container can be made of any shape. This container is in the form of a cross whereas the container 15 is in the form of a star.

While various changes may be made in the 25 detail construction, it shall be understood that such changes shall be within the spirit and scope of the present invention as defined by the appended claim.

I claim:

30 In a fire extinguisher for trees, the combination which comprises a vertically disposed rod having a threaded upper end, a sealed fragile container having loops with openings therein carried by the upper threaded end of the rod 35 with the loops positioned on the rod, locking nuts on the threaded end of the rod for securing the container through the loops thereof in position on the rod, a disc freely slidable on the rod and positioned to engage the container, a 40 spring on the rod positioned to urge the disc toward the container, means anchoring one end of the spring to the rod, and a fusible element secured to the rod and positioned for retaining said disc in spaced relation to said container 45 whereby upon fusing of the element the spring snaps the disc against the container for breaking the container.
